CLAIM

The ornamental design for a wall panel, as shown and described.

DESCRIPTION

FIG. 1 is a front perspective view of a wall panel showing our new design;

FIG. 2 is a front view of the wall panel of FIG. 1;

FIG. 3 is a rear view of the wall panel of FIG. 1;

FIG. 4 is a top view of the wall panel of FIG. 1;

FIG. 5 is a bottom view of the wall panel of FIG. 1;

FIG. 6 is a left-side view of the wall panel of FIG. 1;

FIG. 7 is a right-side view of the wall panel of FIG. 1;

FIG. 8 is an enlarged view of the portion of the wall panel identified by area 8 in FIG. 6;

FIG. 9 is an enlarged view of the portion of the wall panel identified by area 9 in FIG. 6;

FIG. 10 is an enlarged view of the portion of the wall panel identified by area 10 in FIG. 6;

FIG. 11 is a front perspective view of the second embodiment of a wall panel;

FIG. 12 is a front view of the wall panel of FIG. 11;

FIG. 13 is a rear view of the wall panel of FIG. 11;

FIG. 14 is a top view of the wall panel of FIG. 11;

FIG. 15 is a bottom view of the wall panel of FIG. 11;

FIG. 16 is a left-side view of the wall panel of FIG. 11;

FIG. 17 is a right-side view of the wall panel of FIG. 11;

FIG. 18 is an enlarged view of the portion of the wall panel identified by area 18 in FIG. 16;

FIG. 19 is an enlarged view of the portion of the wall panel identified by area 19 in FIG. 16;

FIG. 20 is an enlarged view of the portion of the wall panel identified by area 20 in FIG. 16;

FIG. 21 is a front perspective view of the third embodiment of a wall panel;

FIG. 22 is a front view of the wall panel of FIG. 21;

FIG. 23 is a rear view of the wall panel of FIG. 21;

FIG. 24 is a top view of the wall panel of FIG. 21;

FIG. 25 is a bottom view of the wall panel of FIG. 21;

FIG. 26 is a left-side view of the wall panel of FIG. 21;

FIG. 27 is a right-side view of the wall panel of FIG. 21;

FIG. 28 is an enlarged view of the portion of the wall panel identified by area 28 in FIG. 26;

FIG. 29 is an enlarged view of the portion of the wall panel identified by area 29 in FIG. 26;

FIG. 30 is an enlarged view of the portion of the wall panel identified by area 30 in FIG. 26;

FIG. 31 is a front perspective view of the fourth embodiment of a wall panel;

FIG. 32 is a front view of the wall panel of FIG. 31;

FIG. 33 is a rear view of the wall panel of FIG. 31;

FIG. 34 is a top view of the wall panel of FIG. 31;

FIG. 35 is a bottom view of the wall panel of FIG. 31;

FIG. 36 is a left-side view of the wall panel of FIG. 31;
FIG. 37 is a right-side view of the wall panel of FIG. 31;
FIG. 38 is an enlarged view of the portion of the wall panel identified by area 38 in FIG. 36;

FIG. 39 is an enlarged view of the portions of the wall panel identified by area 39 in FIG. 36;

FIG. 40 is an enlarged view of the portion of the wall panel identified by area 40 in FIG. 36;

FIG. 41 is a front perspective view of the fifth embodiment of a wall panel;

FIG. 42 is a front view of the wall panel of FIG. 41;

FIG. 43 is a rear view of the wall panel of FIG. 41;

FIG. 44 is a top view of the wall panel of FIG. 41;

FIG. 45 is a bottom view of the wall panel of FIG. 41;

FIG. 46 is a left-side view of the wall panel of FIG. 41;

FIG. 47 is a right-side view of the wall panel of FIG. 41;
FIG. 48 is an enlarged view of the portion of the wall panel identified by area 48 in FIG. 46;

FIG. 49 is an enlarged view of the portions of the wall panel identified by area 49 in FIG. 46;

FIG. 50 is an enlarged view of the portion of the wall panel identified by area 50 in FIG. 46;

FIG. 51 is a front perspective view of the sixth embodiment of a wall panel;

FIG. 52 is a front view of the wall panel of FIG. 51;

FIG. 53 is a rear view of the wall panel of FIG. 51;

FIG. 54 is a top view of the wall panel of FIG. 51;

FIG. 55 is a bottom view of the wall panel of FIG. 51;

FIG. 56 is a left-side view of the wall panel of FIG. 51;

FIG. 57 is a right-side view of the wall panel of FIG. 51;
FIG. 58 is an enlarged view of the portion of the wall panel identified by area 58 in FIG. 56;

FIG. 59 is an enlarged view of the portions of the wall panel identified by area 59 in FIG. 56;

FIG. 60 is an enlarged view of the portion of the wall panel identified by area 60 in FIG. 56;

FIG. 61 is a front perspective view of the seventh embodiment of a wall panel;

FIG. 62 is a front view of the wall panel of FIG. 61;

FIG. 63 is a rear view of the wall panel of FIG. 61;

FIG. 64 is a top view of the wall panel of FIG. 61;

FIG. 65 is a bottom view of the wall panel of FIG. 61;

FIG. 66 is a left-side view of the wall panel of FIG. 61;

FIG. 67 is a right-side view of the wall panel of FIG. 61;
FIG. 68 is an enlarged view of the portion of the wall panel identified by area 68 in FIG. 66;

FIG. 69 is an enlarged view of the portions of the wall panel identified by area 69 in FIG. 66;

FIG. 70 is an enlarged view of the portion of the wall panel identified by area 70 in FIG. 66;

FIG. 71 is a front perspective view of the eighth embodiment of a wall panel;

FIG. 72 is a front view of the wall panel of FIG. 71;

FIG. 73 is a rear view of the wall panel of FIG. 71;

FIG. 74 is a top view of the wall panel of FIG. 71;

FIG. 75 is a bottom view of the wall panel of FIG. 71;

FIG. 76 is a left-side view of the wall panel of FIG. 71;

FIG. 77 is a right-side view of the wall panel of FIG. 71;
FIG. 78 is an enlarged view of the portion of the wall panel identified by area 78 in FIG. 76;

FIG. 79 is an enlarged view of the portions of the wall panel identified by area 79 in FIG. 76;

FIG. 80 is an enlarged view of the portion of the wall panel identified by area 80 in FIG. 76;

FIG. 81 is a front perspective view of the ninth embodiment of a wall panel;

FIG. 82 is a front view of the wall panel of FIG. 81;

FIG. 83 is a rear view of the wall panel of FIG. 81;

FIG. 84 is a top view of the wall panel of FIG. 81;

FIG. 85 is a bottom view of the wall panel of FIG. 81;

FIG. 86 is a left-side view of the wall panel of FIG. 81;

FIG. 87 is a right-side view of the wall panel of FIG. 81;

FIG. 88 is an enlarged view of the portion of the wall panel identified by area 88 in FIG. 86;

FIG. 89 is an enlarged view of the portions of the wall panel identified by area 89 in FIG. 86; and,

FIG. 90 is an enlarged view of the portion of the wall panel identified by area 90 in FIG. 86.

The wall panel is shown with solid line symbolic breaks along its length and width. The symbolic break lines and the portions between the symbolic break lines form no part of the claimed design. The dash-dash broken lines in the drawings depict portions of the wall panel that form no part of the claimed design. The dash-dot-dash broken lines in the drawings represent boundaries of the enlarged views and form no part of the claimed design.
